UNITED STATES PATENT OFFICE.

JOHN McGHEE, OF GLASGOW, SCOTLAND.

COMBINED NUT AND PIPE WRENCH.

Application filed November 9, 1920. Serial No. 422,929.

To all whom it may concern:

Be it known that I, JOHN McGHEE, of Morrison Villa, Tollcross, Glasgow, Scotland, engine fitter, have invented a certain 5 new and useful Combined Nut and Pipe Wrench (for which I have filed an application in Great Britain, No. 27502, November 7, 1919), of which the following is a specification.

10 My invention consists in an improved combined nut wrench and pipe wrench and has for its object to provide one of a cheap, simple, and efficient nature.

In carrying out my invention, I provide 15 an ordinary monkey wrench or nut wrench having its usual sliding jaw which works up and down in the casing, which casing carries integrally as one jaw the lower jaw of the nut wrench and the upper jaw of the 20 pipe wrench. To this casing the shank of the lower jaw of the pipe wrench is pivoted by a pin passing through a hole in the shank and a hole or slot in the casing. When used as a pipe wrench the under side of the lower 25 jaw of the nut wrench and the pivoted lower jaw of the pipe wrench are caused to grip the pipe or other round article by the operation of the handle of said shank.

In order that my invention may be properly understood and readily carried into effect, I have hereunto appended one sheet of drawings, of which—

Figure 1 is a side elevation of a combined nut wrench and pipe wrench, constructed 35 and arranged in accordance with my invention;

Fig. 2 is a similar view of the same, at right angles to Fig. 1;

Fig. 3 is a detail elevation of the same in 40 use; and

Fig. 4 is a similar view showing a modification.

The fixed jaw 1 and straight shank 2 are of the usual construction in a nut wrench, 45 and said shank is provided on the rear side with worm rack teeth 3. The sliding jaw B has the usual casing which is arranged to slide on the shank 2, and in the said casing is mounted a worm F which engages the 50 worm teeth 3 and hence permits the jaw B to be adjusted. Said jaw B forms the lower jaw of the nut wrench, and the upper jaw of the pipe wrench, in accordance with my invention, and is serrated at H as shown.

55 The lower jaw of the pipe wrench comprises a pair of members G which are ar-

ranged on opposite sides of the casing and are connected together by and are integral with a channelled shank A, the sides E of which are spaced from opposite sides of the 60 shank 2, as shown in Fig. 2. Said jaw members G are pivotally connected to the casing of the jaw B by a pivot bolt C which may be arranged in either one of a series of openings D with which the casing is provided, 65 and hence the pipe wrench jaw members G may be adjusted toward or from the jaw B, as may be required by the diameter of the pipe or other work to be engaged. Said jaw members G are connected by a spacer 70 K, and are serrated at H on the edges which are opposed to the jaw B, as shown.

When used as a pipe wrench, the under side of the lower jaw of the nut wrench and the pivoted lower jaw of the pipe wrench, 75 are caused to grip the pipe or other article, as indicated at O in Fig. 3, and at M in Fig. 4, by the operation of the shank A, said shank and the shank 2 being grasped by the user, as will be understood. By adjusting 80 the jaw B toward or from the jaw 1, by means of the worm F and worm teeth 3, a nut may be grasped and held between the jaws 1 and B as shown at O in Fig. 3, or at L in Fig. 4.

Fig. 4 illustrates a slightly modified construction, in which the adjusting worm F' is in the same side of the casing as the jaw B and the worm teeth 3^a are on the front side of the shank 2 and in which the pivot C 90 is arranged in a slot N instead of a series of holes.

Having thus described my invention, I claim:

1. A combined nut wrench and pipe 95 wrench, comprising a shank, a fixed jaw thereon, a sliding jaw, means to adjust the sliding jaw with reference to the fixed jaw, said sliding jaw forming the lower jaw of the nut wrench and also the upper jaw of 100 the pipe wrench, and a third jaw pivotally connected to the sliding jaw and also having an operating shank, said third jaw forming the lower jaw of the pipe wrench.

2. A combined nut wrench and pipe 105 wrench, comprising a shank, a fixed jaw thereon, a sliding jaw, means to adjust the sliding jaw with reference to the fixed jaw, said sliding jaw forming the lower jaw of the nut wrench and also the upper jaw of 110 the pipe wrench, and a third jaw pivotally and adjustably connected to the sliding jaw

and also having an operating shank, said third jaw forming the lower jaw of the pipe wrench.

3. A combined nut wrench and pipe wrench, comprising a shank, a fixed jaw thereon, a sliding jaw, means to adjust the sliding jaw with reference to the fixed jaw, said sliding jaw forming the lower jaw of the nut wrench and also the upper jaw of the pipe wrench, and a third jaw pivotally

connected to the sliding jaw and also having an operating shank, said third jaw forming the lower jaw of the pipe wrench, and comprising a pair of members spaced from opposite sides of said first-named shank, and said second-named shank being of channel form.

In witness whereof I affix my signature.

JOHN McGHEE.
